CLAIM

The ornamental design for a photo holder, as shown and described.

DESCRIPTION

FIG. 1 is a perspective view of a photo holder embodying my new design;

FIG. 2 is a front elevational view thereof, the rear elevational view being a mirror image thereof;

FIG. 3 is a left side elevational view thereof;

FIG. 4 is a right side elevational view thereof;

FIG. 5 is a top plan view thereof; and,

FIG. 6 is a bottom plan view thereof.

The portions shown in broken lines are for illustrative purposes only; and form no part of the claimed design.
